UNITED STATES PATENT OFFICE.

DAVID P. THOMPSON, OF CHICAGO, ILLINOIS, ASSIGNEE TO INLAND STEEL COMPANY,
OF INDIANA HARBOR, INDIANA, A CORPORATION OF DELAWARE.

APPARATUS FOR HEATING ROLLS OF ROLLING MILLS.

Application filed May 13, 1922. Serial No. 560,549.

To all whom it may concern:

Be it known that I, DAVID P. THOMPSON, a citizen of the United States, residing at Chicago, in the county of Cook and State of Illinois, have invented a new and useful Improvement in Apparatus for Heating Rolls of Rolling Mills, of which the following is a specification.

My invention relates, more particularly to the rolling of metal sheets involving the rolling of the sheets from heated sheet-forming bars by passing them through relatively large solid rolls commonly constructed of chilled gray iron.

The common practice in the rolling of sheets is to heat the rolls to the desired temperature for rolling the desired greater widths of sheets of relatively thin gage, by first passing between the rolls a highly heated sheet-forming bar of a relatively short length and thereafter, in succession, passing between the rolls bars of greater lengths, until the rolls have been heated to the desired degree for the rolling of bars of the length for producing the desired relatively wide sheets, the rolls being heated by the friction produced between them and the bars and by the heat radiated from the bars.

The practice above stated has many disadvantages among which are that it requires a relatively great length of time to heat the rolls for the rolling of wide sheets of thin gage. The sheets rolled from the bars of the shorter lengths are of much less value than those rolled from the longer lengths due to their narrow widths and relatively heavy gage; the rolls oftentimes become fractured during this heating operation, and particularly upon the first application of heat thereto, due to the existence of foundry strains in the rolls; and the surfaces of the rolls are soon impaired, by the heating up of the same as above stated, for the proper rolling of the sheets. My object, generally stated, is to overcome the disadvantages of prior practices and especially those above enumerated particularly with a view to reducing the cost of rolling sheets and increasing the capacity of the rolls for rolling, during the period of time in which the rolls are in operation, the wider sheets of narrow gage.

Referring to the accompanying drawings:

Figure 1 is a view in front elevation of a 55 rolling mill equipped with means for preliminarily heating the rolls in accordance with my invention and suitable for practicing my improved process. Figure 2 is a section taken at the irregular line 2—2 60 on Fig. 1 and viewed in the direction of the arrows. Figure 3 is a broken enlarged sectional view taken at the line 3—3 on Fig. 1 and viewed in the direction of the arrows. Figure 4 is an enlarged plan sectional view taken at the line 4—4 on Fig. 2 and viewed in the direction of the arrows. Figure 5 is a plan sectional view taken at the line 5—5 on Fig. 2 and viewed in the direction of the arrows. Figure 6 is a face 70 view of one of the plurality of electrical heating units employed, with certain portions thereof broken away to disclose interior details. Figure 7 is a section taken at the line 7—7 on Fig. 6 and viewed in the 75 direction of the arrows; and Figure 8 a section taken at the line 8 on Fig. 6 and viewed in the direction of the arrows.

In accordance with my invention I preliminarily heat, to the desired temperature, 80 by electric current, the pair of cooperating rolls to be used for rolling the sheets throughout their cross section and substantially throughout the length of the main body portions of the rolls, the rolls being 85 heated preferably to a temperature of about 300° F. at their peripheries at a point midway between their ends, thereby to cause these rolls to be conditioned for properly rolling sheets of relatively great width and 90 thin gage.

In the drawings the invention is shown as applied to a rolling mill of common construction and involving generally stated a framework affording the uprights 9 spaced 95 apart in which the necks 10 of the two rolls 11 one of which superposes the other, are journaled, the ends of the rolls 11 being adapted for connection therewith of wabblers through the medium of which these 100 rolls are driven. It may be here stated that according to common practice the lower roll is of true cylindrical form, and the periphery of that portion of the upper roll which is contacted by the sheet-forming bars in 105 the rolling operation, is circumferentially slightly concaved in order that these rolls shall properly function to produce sheets

of uniform thickness throughout their extent, after the rolls have become properly heated.

The features of the specific construction selected for the purpose of illustrating my invention which features are shown and described but not claimed herein, are the invention of Robert L. McIntosh and are shown and claimed in his copending application Serial No. 562,552, filed on even date with the present application.

The particular construction of means illustrated for preliminarily heating the rolls comprises a housing for application to the pair of rolls, which is provided with a series of electrical heating elements positioned to contact with substantially the entire peripheries of the portions of the rolls between the necks thereof. The housing shown is formed of two similar sections 12 adapted to be applied to the rolls from opposite sides thereof and be secured in place thereon. Each section is shown as formed of the elements 13, 14 and 15 in the form of angle-bars spaced apart lengthwise of the rolls, the upper ends of the elements 13, 14 and 15, as to each section, being connected with a plate 16 and the lower ends with a plate 17, the plates 16 and 17 containing apertures, certain of which open through the margins of the plates, for receiving bolts 18 through the medium of which the housing sections are releasably secured in position on the rolls. The lower ends of the elements 13 and 15 are provided with legs 19 in which a shaft 20, carrying a roller 21, is mounted, and the upper ends of the elements 13 and 15 are provided with upwardly extending handle-ports 22. Each of the housing sections 12 also comprises a member, represented at 23, of sheet like form, this member being preferably of flexible sheet-metal and contoured to substantially conform to the contour of the portions of the peripheries of the rollers which it opposes as shown in Fig. 2. Each member 23 is preferably rigidly secured, as by riveting, or otherwise, to those portions of the angle-shaped elements 13, 14 and 15 which parallel the rolls, at the upper and lower portions of the members 23, but are preferably disconnected from the said elements at those portions thereof between horizontal planes 55 passing through the centers of the rolls.

The electrical heating elements forming a portion of each of the sections 12, and shown as of the common "space-heater" type, are represented at 24. These heating elements, which are interposed between the rolls and the members 23, contact with the peripheries of the rolls as represented in Fig. 2 and are grouped in any desirable arrangement, as for example that shown wherein they extend in a direction length-

wise of the rolls and in spaced relation to each other. Each heating element 24 is provided at opposite ends with angle-shaped brackets 25 which extend through openings 23a in the member 23, these brackets serving as terminals for the heating elements and through the medium of which these elements are electrically connected together in series, or in parallel, as desired, and with any suitable source of current supply. In the particular arrangement shown all of the brackets 25 at one end of the heating device are connected with one of the main line current wires and all of the brackets at the other end are connected with the other of the main line current wires.

Each of the heating elements 24 is shown as comprising a metal casing 26, containing a coil of any suitable electrical resistance wire 27 extending substantially the full length of the element and wound about a core 28 of mica, or any other suitable insulating material, there being interposed between the bottom wall 29 of the casing 26 and the coil 27 a sheet 30 of insulating material, as for example mica. A strip of metal 31 directly underlies the upper wall portion 32 of the casing 26 and has interposed between it and the coil 27 a sheet 33 of insulating material as for example mica. Each element 24 is provided at each end with an eyelet 34 which flatwise bears at a shoulder-portion 35 thereof against the insulating strip 30 and extends through openings in the strips 31 and 33 and cut-out portions 36 in the upper portions 32 of the casing 26, these eyelets also extending through metal washers 37 and through openings in the base portions of the brackets 25. A mica washer 38 extends between each washer 37 and the iron strip 31, and the openings through the strip 31 are such size that the walls thereof are out of contact with the eyelets 34. Each eyelet 34 being in electrical contact with the adjacent bracket 25, is in electrical contact with one of the terminals of the coil 27.

In the particular construction illustrated means are provided whereby the sheet portions 23 may be bent into such form that the heating elements 24 will contact with the peripheries of the rolls throughout substantially their entire extent as shown in Fig. 2, these means comprising a U-bar 39 which extends at its cross-bar portion 40 against the outer surface of the sheet 23 and in a plane parallel with the axes of the rolls, the outer ends of the arms of the yoke 39, and represented at 41, being threaded and extending through openings in a channel-bar 42 secured to, and extending crosswise of, the members 13, 14 and 15, the threaded ends of the arms 41 being provided with pairs of nuts 43 by means of which the de-

sired pressure may be exerted and maintained against the sheeting 23, through the yokes 39 for deforming these sheets into the desired shape as above stated, it being understood that after these sheets have once been deformed by adjusting the yokes 39 as stated to adapt them to rolls of a particular size, no further adjustment is required. In the use of the apparatus shown the sections 10 12 are applied to opposite sides of the assembled rolls to the position shown in Fig. 2, the provision of the rollers 21 and the handle portions 22 serving to permit these sections to be wheeled to the position for application to the rolls, after the manner of a wheelbarrow. With the sections 12 in place on the rolls and the desired circuit connections made for supplying current to the various heater elements 24, the current is permitted 15 to pass through these elements, the heat generated thereby radiating into the rolls until the rolls are heated to the desired degree, as for example the temperature above specified. It has been found by actual demonstration 20 that the rolls even when of the largest dimensions commonly used in rolling mill practice, may be heated to a degree sufficient for the starting in of the rolling of relatively wide sheets of thin gage, and that 25 such heating may be effected in a relatively short length of time. Thus the many disadvantages resulting from prior practices and above pointed out are eliminated, and great economy of structure and in the operation of mills, is effected.

It has also been found in the actual practice of the invention that the heating up of the rolls in accordance with the invention, as explained, almost entirely eliminates the 30 danger of fracturing the rolls during the initial heating up of the same, from foundry strains therein, the heating of the rolls as stated, and which it will be understood involves a relatively gentle application of heat, 35 as compared with the heating of the rolls by forcing heat into the latter from the relatively highly heated bars by friction of the bars therewith and by heat radiated therefrom, appearing to produce an action on the 40 rolls in the nature of annealing.

It will be understood that the preliminary heating of the rolls as stated may be effected either when the rolls are assembled with the other parts of the mill, or when 45 disassembled therefrom, as for example while supported in racks from which they

may be removed, for assembly with the other parts of the mill, after the preliminary heating. Thus a mill may be continuously operated, for the production of wide, narrow 50 gage, sheets, except for such interruptions as result from the mere changing of rolls, as the preheating of the rolls makes possible the continued production of such sheets, without requiring the rolling of narrow, 55 heavy gage, sheets, as is necessary where the substituted rolls are assembled, in cold condition, with the other parts of the mill.

While I have described a certain particular apparatus embodying my invention, and by 60 which my improved method may be practiced, I do not wish to be understood as intending to limit it thereto as the structure may be variously modified and altered without departing from the spirit of the invention, and the improved method practiced by 65 employing other apparatus.

What I claim as new, and desire to secure by Letters Patent, is:

1. Apparatus for heating rolls of rolling 70 mills, said apparatus comprising a sheet like member adapted to be positioned at the periphery of a roll, electrical heating elements positioned upon the sheet like member for heating the rolls and means adapted for 75 positioning the sheet like member adjacent the roll.

2. Apparatus for heating rolls of rolling 80 mills, said apparatus comprising a sheet like member adapted to be positioned at the periphery of a roll and to conform approximately to the roll contour, electrical heating elements positioned upon the sheet like member for heating the rolls and means adapted for 85 positioning the sheet like member adjacent the roll.

3. Apparatus for heating rolls of rolling 90 mills, said apparatus comprising a heat insulated blanket element adapted to be positioned about the periphery of the rolls and 95 electrical heating elements upon the inner face of the blanket element and adapted to heat the roll.

4. Apparatus for heating rolls of rolling 100 mills, said apparatus comprising a heat insulated blanket element adapted to be positioned about the periphery of the rolls and electrical heating elements upon the inner 105 face of the blanket element and adapted to engage the roll surface to heat the roll.

DAVID P. THOMPSON.
